UNITED STATES PATENT OFFICE.

RALPH J. QUELLE, OF BURLINGTON, IOWA, ASSIGNOR OF ONE-HALF TO JAMES MOIR,
OF BURLINGTON, IOWA.

VALVE SYSTEM.

1,213,536.

Specification of Letters Patent. Patented Jan. 23, 1917.

Application filed January 21, 1916. Serial No. 73,428.

To all whom it may concern:

Be it known that I, RALPH J. QUELLE, a citizen of the United States of America, residing at Burlington, in the county of Des Moines and State of Iowa, have invented 5 certain new and useful Improvements in Valve Systems, of which the following is a specification, reference being had therein to the accompanying drawing.

10 This invention relates to engines and has special reference to a cylinder valve system which may be employed upon explosive engines of any type, air or gas engines, and in fact any other suitable or desired motor 15 wherein the same mechanical construction or system may be adopted.

Another object of this invention is the production of a simple and efficient valve system for a four-cycle engine or motor, and 20 has for its object the production of a simple and efficient means for feeding the gases to the explosive cylinders and conveying the exhaust gases therefrom at predetermined times through the medium of the rotating 25 valve.

A still further object of this invention is the production of a simple and efficient means for lubricating the rotating valve so as to cause the valve to operate with the 30 least amount of friction.

With these and other objects in view this invention consists of certain novel combinations, constructions, and arrangements of parts as will be hereinafter fully described 35 and claimed.

In the accompanying drawings:—Figure 1 is a central longitudinal section through the motor showing the rotary valve in side elevation. Fig. 2 is a top plan view of the 40 motor showing the manifold removed. Fig. 3 is a bottom plan view of the upper section of the valve casing showing the rotary valve positioned therein. Fig. 4 is a top plan view of the lower section of the valve casing, the rotary valve being removed therefrom. Fig. 5 is a top plan view of the 45 explosive cylinders with the upper valve casing removed or in other words a section taken on line 5—5, of Fig. 1, looking in the direction of the arrow. Fig. 6 is a section taken on line 6—6, of Fig. 1. Fig. 7 is a section taken on line 7—7, of Fig. 1. Fig. 8 is a section taken on line 8—8, of Fig. 1. Fig. 9 is a section taken on line 9—9, of 55 Fig. 1. Fig. 10 is a plan view showing the

arrangement of the ports in the rotary valve, the valve being shown in diagram to more clearly illustrate the different arrangements of the ports. Fig. 11 is an embodiment of the invention wherein the valve casing is positioned to one side of the explosive cylinder, thereby producing what is known as the L-head type. Fig. 12 is a vertical section through an embodiment of the invention wherein two valves are employed, 60 one above the explosive cylinder and one to the side thereof known as the overhead and L-head type. It, of course, should be understood that the valve may be so placed as to produce what is known as a T-head type 65 without departing from the spirit of the invention by having two valve casings, one casing being positioned upon each side of the explosive cylinder. Fig. 13 is a transverse sectional view through the upper section 70 of the valve casing. Fig. 14 is a transverse sectional view through the lower section of the valve casing.

By referring to the drawings it will be seen that 1 designates the crank casing which 80 is formed of a plurality of sections to facilitate the disassembling of the casing when so desired as is usual with such engines. A crank shaft 2 is placed within the crank casing 1 and is journaled upon the standards 3 85 as illustrated in Fig. 1 of the drawings. A fly wheel 4 of suitable construction is carried by the crank shaft 2, and the crank shaft 2 may be connected to any suitable mechanism which it is desired to drive by 90 means of a connecting shaft 5 illustrated in Fig. 1 of the drawings.

A cylinder supporting housing 6 comprising the upper half or section of the crank casing is supported upon the lower half of 95 the crank casing 1 as illustrated in Fig. 1, and is provided with a plurality of ports 7 in the top thereof which communicate with the respective explosive cylinders hereinafter more fully described. The crank shaft 100 2 is provided with a gear 8 which meshes with a gear 9 carried by a stub shaft 10, and this shaft 10 carries a sprocket wheel 11 over which sprocket wheel 11 passes a sprocket chain 12, the chain 12 in turn passing over a sprocket wheel 13 carried by the shaft 14 which supports the rotary valve 15. A sprocket wheel 16 is also supported upon the crank shaft 2, around which a sprocket chain may be passed if so desired for driv- 110

ing the valve 15 direct from the shaft 2 according to the direction of travel in which the valve 15 is desired to operate. A generator, magneto or water pump may be 5 driven by means of a chain from this sprocket wheel 16. A pulley 17 is keyed to the shaft 5, and a fan supporting shaft 18 is supported upon the frame 19 as illustrated in Fig. 1 and has its inner end journaled upon the explosive cylinder housing 20 as illustrated in Fig. 1 of the drawings. A pulley 21 is carried by the shaft 18, and a belt of suitable construction may pass over the pulleys 17 and 21 for the purpose of 15 driving the fan 22 carried by the shaft 18 for the purpose of cooling the engine when so desired.

A plurality of explosive cylinders 20 are arranged upon the housing 6, and the explosive chamber 23 of these cylinders 20 communicates with the apertures 7 formed in the housing 6. Although four cylinders 20 are preferably used, it should be understood that any number of cylinders may be 25 used without departing from the spirit of the invention. Piston heads 24 are mounted within the cylinders 23 and are connected by means of piston rods 25 to the respective crank portions of the crank shaft 2. A suitable water jacket 26 may be employed around the explosive cylinder 20 as illustrated clearly in Fig. 1 of the drawings for the purpose of efficiently cooling the explosive cylinder as is usual with such water 35 jackets.

A valve supporting casing is mounted upon the top of the explosive cylinders as will be seen by carefully considering the drawings, and this valve casing comprises 40 a lower section 27 and an upper section 28, which sections are adapted to efficiently register and are provided with a longitudinally extending pocket for fitting snugly around the rotating valve 15. A bearing housing 29 is mounted in each end of the valve supporting casing and supports the bearings 30, which bearings fit snugly around the shaft portion 14 of the rotary valve 15. The several sections comprising 45 the upper and lower sections of the valve casing may be joined or connected together in any suitable or convenient manner for causing the sections to fit snugly around the valve, and by having the sections formed so 50 as to be readily separated, it will be seen that the valve may be readily repaired or cleaned when so desired for the purpose of removing carbon therefrom, and further that by moving the entire valve casing, access 55 may be had directly to the top of the piston heads so as to permit the carbon to be readily and conveniently scraped from the upper end of the piston heads. This is a very important and essential feature in 60 connection with explosive engines, for by

experience it has been found difficult to remove the carbon which accumulates upon the piston heads and the upper end of the cylinder, especially in view of the fact that it has been found practically impossible to obtain free access to these portions of the engine in order that the carbon deposited thereon may be readily removed.

It should be understood that as illustrated clearly in Fig. 6, a water jacket 31 is arranged around the rotary valve 15 and thereby keeps the same cool, the water of course, being supplied to the water jacket 31 in any suitable or convenient manner. An oil lubricating reservoir 32 is placed around the outer portion of the water jacket, and the casings of the valve are provided with a plurality of lubricating supply ports 33 for conveying the lubricant at all times to the rotary valve 15. It should be understood that the oil by being confined in the compartment 32 will be kept quite cool due to the fact that the water jacket is interposed between the rotary valve and the oil compartment, thereby allowing the lubricant to perform its function in the most efficient manner. The lower section 27 of the valve casing is provided with a plurality of zigzag grooves 34 formed upon the concave face thereof, which grooves will cause the lubricant to travel over the entire inner face of the valve housing, thereby producing an efficient means for thoroughly lubricating the entire face of the rotary valve 15. These grooves 34 communicate with the ports 33 thereby permitting a constant supply of lubricant to pass to the grooves 34.

Attention is now called to the fact that each explosive cylinder 20 is provided with a spark plug receiving pocket 35 within which is mounted a spark plug 36, the spark plug being connected in the usual manner with a timer and means for supplying current thereto, which construction is thought unnecessary to illustrate and describe in detail. The spark plugs by being placed in the pocket 35 will be protected from injury and will not be likely to become loose owing to the fact that the securing nut 37 carried thereby is mounted clearly within the pocket 35 which supports the spark plug 36.

It should be understood that the inlet apertures 38 and exhaust apertures or ports 39 are arranged in pairs as illustrated in Fig. 4 in alignment with each other and communicate with the explosive chambers 23 so as to permit the exhaust gases to be discharged therefrom and the inlet gases to be admitted thereto when the proper apertures formed in the rotary valve 15 register with the respective ports 38 and 39.

By carefully considering Fig. 3 and also the diagram view in Fig. 10 it will be seen that the inlet ports 40 and 41 adapted to cooperate with each explosive cylinder are 130

arranged in staggered relation, that is to say, the inlet port for the first explosive cylinder is positioned slightly in the rear of the exhaust port so as to cause the ports in the rotary valve to communicate with the ports in the different cylinders at proper times to admit and discharge the gases. It should be understood that the burned gases must be eliminated before a charge of gas can be taken in. The diagram in Fig. 10 shows this by rotating from bottom to top of figure; the exhaust ports are to the left of the intake ports. This zigzag rotation may also be reversed. That is, the exhaust ports may be placed on the right of the intake ports but this would cause the staggered effect to be in the opposite direction as it is on the drawing. These ports are so arranged upon the rotary valve 15 as to cause the cylinder marked A to take in gases to the intake port 40 in the valve 15, the piston head 24 assuming the position shown in Fig. 6, this being the intake stroke. Referring to the position of the piston head 24 in Fig. 7, it will be seen that the piston head is now upon its compression stroke, the inlet port 40 being closed due to the rotation of the valve 15, and the gases admitted into the explosive cylinder 23 being compressed at this time.

By considering Fig. 8 which is a section taken on line 8-8, it will be seen that the piston head 24 is upon its exhaust stroke, the exhaust aperture or port 41 communicating with the discharge or exhaust port 42 formed in the upper section 28 of the valve casing. In Fig. 9 the piston is upon its power stroke or in other words at the time of the explosion of the gases and the piston 40 is ready for its descent, both the exhaust and inlet ports are closed due to the proper rotation of the valve 15.

It should be understood that Figs. 6, 7, 8 and 9 are merely arranged to agree with the respective section lines taken on Fig. 1 and do not show the sequence of operation but merely show the different positions of the piston heads. It should be understood, however, that each piston is adapted to operate as shown in the respective Figs. 6, 7, 8 and 9, one cylinder at a time receiving the power stroke and the other cylinders in turn taking in gas, compressing the gas and then exhausting the gas so as to have each piston operate at a different time.

It, of course, should be understood that should it be so desired, the pistons may be multiplied or decreased in number to suit the convenience of the operator or manufacturer of the engine or motor.

It should be understood that the upper section of the valve casing is provided with a plurality of ports 42 and 43, the ports 42 indicating the exhaust ports communicating with the manifold 44, and the ports 43

indicating the inlet ports communicating with that portion of the manifold 44 which supplies the gases to the explosive chambers. The lower section 27 of the valve casing is also provided with a plurality of inlet ports 38 and a plurality of exhaust ports 39 as above explained which communicate with the apertures formed in the rotary cylinder or valve.

As illustrated clearly in Fig. 11, the engine may be arranged for producing what is known as an L-head type, wherein the valve casing 45 is positioned to one side of the explosive chamber 46 and is provided with a rotary valve 47 similar to the valve 15 above described. A spark plug 48 is mounted within the pocket 45 formed upon the top of the explosive chamber 46, otherwise the engine is similarly constructed to that above described.

In Fig. 12 there is shown an embodiment of the invention wherein two rotary valves are employed, each valve being positioned in a separate casing, one casing 50 being placed upon the top of the explosive chambers and the other casing 51 being placed upon the side thereof for producing what is known as an L-head type of engine. As above described the same structure may be so modified as to produce the common T-head type of engine without departing from the spirit of the invention so long as the same construction is employed.

The lower portion of the crank case is adapted to be filled with lubricating oil, and an oil pump of suitable construction is adapted to coöperate therewith for the purpose of forcing oil up into the oil reservoir 32 and to other points of the machine which are desired to lubricate. It, of course, is necessary to provide an overflow of suitable construction in the reservoir 32 in order that such overflow may be returned to the crank case. Of course, it should be further understood that means may be provided to permit the insertion of lubricant into the crank case of the engine.

The reservoir 32 is provided with a plurality of division plates or partitions 32', separating this reservoir into compartments 115 so as to permit the free lubrication of the several parts of the rotating valve without regard to the angle or position of the engine. These partitions 32' will cause the lubricant to remain at a predetermined level notwithstanding the position of the engine. It, of course, should be understood that suitable inlets may be provided to permit the interior of the reservoir to be inspected when so desired.

Having thus described the invention what is claimed as new, is:—

1. An engine of the class described comprising a plurality of explosive cylinders, a detachable valve casing supported thereby,

a rotary valve positioned within said detachable valve casing, said valve provided with a plurality of ports formed therein, said valve casing provided with a plurality of ports communicating with said ports in said valve and also communicating with said explosive cylinders for controlling the passage of gases to and from said cylinder through said valve, said rotary valve provided with a projecting end shaft, bearings supporting said end shaft, means for supplying lubricant to the periphery of said rotary valve, a water jacket formed around said rotary valve within said valve casing, and an oil reservoir formed within said valve casing and positioned upon the outside of said water jacket for facilitating the

cooling of the lubricant before being admitted to said rotary valve.

2. An engine of the class described comprising an explosive cylinder, a valve casing supported thereby, a rotary valve positioned within said valve casing, means for supplying lubricant to the periphery of said rotary valve, a water jacket formed around said rotary valve within said valve casing, an oil reservoir formed within said valve casing and positioned upon the outside of said water jacket for facilitating the cooling of the lubricant before being admitted to said rotary valve.

In testimony whereof I hereunto affix my signature.

RALPH J. QUELLE.
